United States Patent Office

Des. 226,498
Patented Mar. 13, 1973

226,498

LAMP

John J. Misenko, 6179 Stratford Drive,
Parma Heights, Ohio 44130

Filed Dec. 1, 1971, Ser. No. 203,950

Term of patent 14 years

Int. Cl. D26—05

U.S. Cl. D48—20 C

FIG. 1 is a side elevational view of a lamp showing my new design,

FIG. 2 is a top plan view thereof,

FIG. 3 is a bottom plan view thereof. The shading on the simulated ball is partially shown for convenience of illustration it being understood that the shading is continuous over the surface of the ball.

I claim:

The ornamental design for a lamp, substantially as shown.
